H. MOHR.
AUXILIARY CYCLE REST,
APPLICATION FILED SEPT. 3, 1919.

Patented Nov. 2, 1920.

Henry Mohr; Inventor.
By his Attorney, *Lawrence J. Augur*

UNITED STATES PATENT OFFICE.

HENRY MOHR, OF LONGFORD, TASMANIA, AUSTRALIA, ASSIGNOR TO A. G. WEBSTER & SONS, LIMITED, OF HOBART, AUSTRALIA.

AUXILIARY CYCLE-REST.

1,357,890.

Specification of Letters Patent.

Patented Nov. 2, 1920.

Application filed September 3, 1919. Serial No. 321,414.

To all whom it may concern:

Be it known that I, HENRY MOHR, of Longford, in the State of Tasmania, Commonwealth of Australia, engineer, and a subject of the King of Great Britain, have invented certain new and useful Improvements Relating to Auxiliary Cycle-Rests, of which the following is a specification.

This invention has reference to means for supporting motor or other cycles in an upright or nearly upright position when stationary or to assist in placing the same upon the rests usually carried upon the machines so that when not running the tires may be relieved of weight.

Users of motor cycles, upon dismounting for short periods usually lift the machine on to the back rest. In a modern high powered motor cycle, to place the rear wheel rest in position, involves lifting directly a weight of some 150 pounds, which the rider is liable to find fatiguing if constantly repeated.

It is partly to avoid this objectionable practice that the invention has been devised, according to which a flexibly mounted strut is provided with the machine, to which it is attached, and the joint of the strut may be fitted with means to keep it at a fixed determined angle with its support while in use. Further, by means of the flexibly mounted prop the operation of raising the machine on to its rest is facilitated as the prop may be used as the purchase upon which to move the cycle backward in placing it upon the rest.

By means of the said strut a machine can be temporarily and safely supported when left by the rider.

But in order to fully understand the invention reference is made to the accompanying drawing, in which,

Figure 1 is a perspective view of the rear wheel of a motor cycle fitted with the flexibly mounted prop.

Fig. 2 is a side elevation of the same shown broken off short and jointed with its supporting spindle that is attachable to the cycle frame. This figure is shown upside down in order to save space on the drawing.

Fig. 3 is a like view of part of the strut illustrating the locking head.

Fig. 4 shows a cycle wheel in end elevation inclining against the struttled support. 55

Fig. 5 is a detail view of the locking head and swiveling socket jointing with same.

Fig. 6 is the ordinary spring cradle attachable by a clip to the machine frame for carrying the strut when not in use, and 60

Fig. 7 is another clip for so holding the strut and showing spring controlled means for retaining the same in the clip or cradle.

Attached to a convenient part of the frame 8 near the top is the spindle 9 that 65 is held in place by the nuts 10 and spring washer 11. On the other end of the spindle is a swiveling head piece 12 that is retained on the spindle by the pin 13. The head 12 is turned to a nice fit on the spindle 70 and is adapted to longitudinal and rotary movements thereon. On the extreme end of the spindle is a lug 14 and a corresponding socket 15 is in a central opening in the swiveling head in which the lug will come 75 when the head is slid backwardly on the spindle, the end of the spindle projecting into the said opening. On the upper side of the said head is a projection or stop 17.

The strut 18 is articulated to the swiveling head 12 through the bolt 19 and in the head of the strut is a socket 15^a and also a projection or stop 16 that is adapted to come against said stop 17 on the swiveling head when the strut is at an obtuse angle 85 with the spindle 9. When in this position the socket 15^a should coincide with the slot 15 in the swiveling head and the two articulated parts can then be slid on to the lug 14 on the spindle to lock the same thereto. 90

In order to provide for locking the strut at more than one angle with the spindle 9, such as might be necessary when propping the machine on sloping ground, the strut head can be fitted with more than one notch 95 15^a which, as the strut is turned about the bolt 19, will come opposite the lug 14 on the spindle while coinciding with the notch or opening 15. While in this position the parts can be brought into engagement with lug 14 thereby locking the strut. By providing the notch 15 in the opening in the swiveling head it will be evident that the head can be locked to the fixed spindle 9 when it is slid inward longitudinally thereon.

By virtue of the swiveling head the strut

is flexible on its mounting and can be swung from side to side when not locked and brought toward a horizontal position and housed when not in use. For this purpose 5 a clip or cradle 20 is provided in a bracket 21 held upon a bar 22 at the rear of the machine. The cradle is lined with a suitable soft resilient substance and is provided with a cover plate 23 pivotally mounted on 10 the bracket. A headed spindle 24 passes downwardly through the plate and is fitted with an encircling spring 25 and a tension nut 26 the spring bearing between the nut and the under side of the bracket to keep 15 the cover plate over the cradle to retain the strut therein.

The ground end to the strut is forked or provided with other means, such as a disk, to prevent the end digging into soft ground 20 and the top end or head of the strut may be formed with a finger 27 (Fig. 5), in lieu of the stop 16, that will come in contact with the swiveling socket or head 12 when the strut is at an obtuse angle with the spindle 9.

25 Instead of the cradle 20 the ordinary spring clip shown in Fig. 6 may be used attached to the bar 22, but the cradle and cover plate is preferred for the purpose indicated. The machine is fitted with the 30 usual rests 28 that are swung downwardly under the wheels to take the weight of the machine when not in use and so relieve the tires of weight.

In operation, when the rider dismounts, 35 as for instance to open a gate, the cover 23 on the cradle 22 is lifted and the strut let down to contact with the ground when the machine will incline against it safely and conveniently until the journey is resumed.

40 If it be desired to place the machine on the back rest 28 the strut will facilitate the operation owing to its flexible mounting when not locked on the rotatory head 12. To place the rear wheel on its rest the latter is let down together with the strut, which 45 should be inclined toward the rear, and the machine is gently moved backward when the wheel will be raised from the ground by virtue of the purchase taken on the flexibly jointed strut: the weight will then come to 50 rest on the member 28 and the strut can be left as it is or raised, as desired.

The device is light, flexible, economical and easily fixed and the auxiliary side rest 55 will be found especially useful by motor cycle users who are called upon to make fre-

quent stoppages or those who are unable to conveniently lift the weight of a high powered machine.

Having now described my invention what 60 I claim as new and desire to secure by Letters Patent is:—

1. In a motor cycle side rest, a strut on a spindle mounted on the machine frame, a rotatory head on the spindle, maximum 65 stopping means between the strut and head and means for locking the strut on its support in positions at varying angles therewith.

2. In a cycle side rest, a strut, a supporting spindle on the machine frame, a rotatory head slidable on the spindle and with which the strut is jointed, an opening in the 70 head into which the spindle end projects, a lug projecting from the spindle end, a recess in the head opposite the lug and maximum stopping means between the strut and the head, as set forth.

3. In a cycle side rest, a strut, a supporting spindle on the machine frame, a rotatory head on the spindle slidable thereon and with which the strut is jointed, an opening in the head into which the spindle end projects, a lug from the spindle end, a recess in the head opposite the lug and notches 75 or indents in the edge of the head of the strut, as and for the purposes specified.

4. In a cycle rest, in combination, a strut 80 flexibly mounted on a spindle on the machine frame, a rotatory head on the spindle jointed with the strut, maximum stopping means between the strut and head, ordinary U-shaped rests on the machine frame near each wheel, means for housing the strut when not in use and flexible means for retaining the same within the cradle or clip, as and for the purposes specified.

5. In a cycle side rest, a strut, ground holding means on the lower end of same, a 100 projecting spindle on the machine frame, a rotatory head on the spindle slidable thereon jointed to the strut, an opening in the head into which the spindle end projects and is retained, a lug from the spindle end, a recess in the opening in the head opposite the lug, indents in the head of the strut, U-shaped rests on the machine frame near to 105 each wheel and means for holding the strut horizontally in the machine, substantially as herein described.

In witness whereof I affix my signature.
HENRY MOHR.
